WILLET C. WELLS AND FRANK E. WELLS, OF COLUMBUS, OHIO.

MEANS FOR INCREASING THE EFFICIENCY OF FUEL FOR MOTIVE POWER.

1,099,411.

Specification of Letters Patent.

Patented June 9, 1914.

Application filed December 31, 1904. Serial No. 239,256.

To all whom it may concern:

Be it known that we, WILLET C. WELLS and FRANK E. WELLS, residing at Columbus, in the county of Franklin and State of Ohio, have invented certain new and useful Improvements in Means for Increasing the Efficiency of Fuel for Motive Power, of which the following is a full, clear, and exact description, such as will enable those skilled in the art to which it appertains to make and use the same.

Our invention pertains to apparatus for converting the chemical energy of fuel into mechanical force, without loss of heat energy, by expanding compressed air by the heat and gases of combustion of fuel, said combustion being supported by the compressed air to be thus expanded. The thus expanded compressed air being applied directly to a turbine motor; the volume of the thus expanded compressed air, thus applied, being regulated to meet the varying requirements of the motor. The pressure of the compressed air entering the furnace being practically uniform, it follows that the pressure within the furnace remains substantially uniform notwithstanding the volume taken from the furnace is variable.

Our apparatus consists of an air compressor, adapted to supply a variable volume of uniformly compressed air; and compressed air storage; a furnace, with means for replenishing fuel therein under air pressure, and in which compressed air supports the combustion of said fuel; a turbine motor actuated by the heat expanded compressed air; and a governor that proportions the volume of the heat expanded compressed air to the requirements of the motor, and thereby, because of uniform pressure of compressed air entering the furnace automatically governs the quantity of compressed air to be heated to meet the requirements of the motor; and means for actuating the said air compressor.

In the accompanying drawings describing our apparatus:—Figure 1 is a vertical cross-section of the apparatus. Fig. 2 is a reverse side view of motor and compressor with outline connections. Fig. 3 is a view of furnace base, showing natural draft intake valve.

Part marked A is an air compressor.

B is a compressed air holder.

C is a furnace.

D is a turbine motor.

E is a conduit pipe, with stop valve E' leading from air compressor A to compressed air holder B.

F is a conduit pipe, with stop valve F' leading from compressed air holder B to furnace base C.

G is a conduit pipe, with governor G', leading from furnace C to motor D.

H is an air pressure regulator.

J is a fuel feeding hopper in connection with furnace C through upper and lower stop valves K and K' through which fuel is fed into the magazine of furnace C.

L and L' are stop-valves through which, when open, furnace C has natural draft.

Shaft M of motor D supports pulley M' and reducing gear connections N and O to crank shaft P of air compressor A. This transmission may be substituted by direct connected dynamo, or other means. Compressed air holder B may receive its initial charge by hand, or from other source. Thus to operate, valves L and L' when open, permit natural draft to support combustion in furnace C. When the furnace is sufficiently heated valves E' and F' leading to and from compressed air holder B are gradually opened, and valves L and L' are closed, thereby delivering heated compressed air and the gases of combustion through conduit G to motor D. The pressure of the compressed air entering the furnace being practically uniform, notwithstanding great variation in its volume, therefore the pressure within the furnace remains substantially uniform however variable may be the demands upon the heat expanded gases for power, and the supply of heat expanded gases and the supply of compressed air to be heated is therefore in exact relation to the requirements of the motor as determined by governor G.

We claim:—

1. An apparatus for converting the chemical energy of fuel into mechanical force by expanding compressed air by the heat and gases of combustion, supported by said compressed air comprising a furnace in which said combustion takes place, an air compressor arranged to supply to said furnace a variable volume of uniformly compressed air, a motor in direct communication with said furnace operated by the heat expanded compressed gases therefrom, and a governor adapted to regulate the flow of said gas from said furnace to said motor.
2. An apparatus for converting the chemi-

cal energy of fuel into mechanical force by expanding compressed air by the heat and gases of combustion supported by said compressed air, comprising a furnace in which said combustion takes place; an air compressor arranged to deliver to said furnace a variable volume of uniformly compressed air, a motor in direct communication with said furnace operated by the heat expanded compressed gases therefrom, connections for operating said compressor from said motor and a governor adapted to regulate the supply of compressed air to said furnace in proportion to the motor load.

3. An apparatus for converting the chemical energy of fuel into mechanical force by expanding compressed air by the heat and gases of combustion supported by said compressed air, comprising a furnace in which said combustion takes place, an air compressor arranged to supply to said furnace a variable volume of uniformly compressed air, a motor, a conduit constructed to prevent loss of heat energy providing communication from said furnace to said motor for conveying the heat expanded compressed gases to said motor to operate the same, and

a governor adapted to regulate the volume of the outflow of said gases from said furnace to meet the variable requirements of said motor.

4. An apparatus for converting the chemical energy of fuel into mechanical force by expanding compressed air by the heat and gases of combustion supported by said compressed air, comprising a furnace in which said combustion takes place, a motor, a conduit constructed to prevent loss of heat energy, providing communication from said furnace to said motor to operate the same, a governor adapted to regulate the volume of the outflow of said gases from said furnace to meet the variable requirements of said motor, and an air compressor arranged to supply to said furnace a volume of uniformly compressed air, varying with the requirements of the motor.

In testimony whereof we affix our signatures, in the presence of two witnesses.
